(76) Inventor: **Moses Davenport**

Moses Davenport
Letters Patent

The Schedule referred to in these Letters Patent (and making part of the same containing a description in the words of the said Moses Davenport himself of his improvement in the machine for cleaning or threshing clover seed or rice

To all to whom these presents shall come

Be it known that Moses Davenport of Phillips in the County of Somerset and State of Maine have invented a new and useful improvement in the Machine for Cleaning or threshing clover seed or rice upon the rubber plates, and that the following is a full and exact description of the construction and operation of the said machine as invented or improved by me. A long trough or oblong box is to be formed of about from five to eight feet long about fifteen inches deep and by from fifteen to twenty four wide according to the power to be employed. It is to be set up in a sloping position having the upper slope and permanently closed and the lower one also closed by means of a sliding gate working between crop bars, at the top and bottom acting as grooves, with a key wedge at each end of the top bar to secure it, at any given elevation, the intention of which gate is to hold down one end of the rubber hose to be described in order to give a strong bite on the seed. There are to be two long openings made between the upper and lower crop bars sufficiently wide for the sliding bars of the rubber to pass and also high enough to admit of friction rollers on the top thereof. An opening is also to be left in the bottom of the trough adjoining this gate for the seed to run out at, and will be about ten inches long, extending from the line of bearing in the friction rollers towards the upper end of the trough (and may be the whole width thereof). The lower rubber plate (which consists of a series of metal plates perforated with holes punched upwards or such other arrangement as will leave a rough surface) is to commence from the upper end of this opening and be let down or sunk some short distance just below the surface of the trough bottom that the seed may fall into it (and will be from one and a half

half to three feet long running up the trough. Above this rests the upper rubber of the same dimensions bringing the two rough sides in contact, and is secured to the rubber frame, which bears on the top of it. This frame consists of two long sliding bars say about two thirds of the length of the trough which are set up edge wise & their lower ends pass through the openings already described in the lower gate, the remainder lies along the bottom of the trough having the upper rubbers secured to them & the balance of their length is formed into a kind of rack, consisting of narrow slips say from four to six inches deep & of the same length as the width of the trough to be secured to the under edge of the sliding bars at intervals of about six inches apart. At the upper end down on the top of these sliding bars is fastened on a heavy weight in the form of a head block or box, of say about two feet in length & the other dimensions to fit the trough, it may be of a box, filled with weights during the operation and then removed for the transportation of the machine elsewhere, as three hundred weight nearly may be requisite in order to effect the purpose that of giving leverage or bearing enough on the rubbers from the fulcrum at the other end of the sliding bars through the lower gate, to clear the seed. The upper end of this box has a row of teeth at the bottom to descend about the same depth as the narrow slips of the rack, and the top of this same end has a projection with a slit in it at each side, in order to receive therein an arm to each (turning upon a pin or pivot) of about fifteen inches in length to project forward where they are terminated in other slits to receive one other arm to each joint also by a pin or pivot joint the second one to be somewhat shorter than the first & is to terminate in a pointed edge which falls by means of the pointed arms to the bottom of the trough where it (or rather both pointed ends) rest in a notch cut for the purpose. in each side bar of another short rack, at this upper end of said trough (and which side bars work through openings left for that purpose at the bottom of the upper end piece) are connected by cross bars lying flat on the bottom of said trough, presenting say a width of about five inches, the length equal to the width of the trough & the upper edge bevelled to a sharp one with the lower edge squared at a right angle equal to the

the depth of the bar so as to shove the said ~~and~~ hulls, downwards or toward the rubber plates. Between this rack & the upper end of the head block is placed a sliding bar or plate to rise up & down in a groove cut on the sides of the trough for that purpose which is intended as a means of feeding the rubber plates with regularity having slits at each side for the reception of the long arm. The short arm above mentioned has a pin passing through it ~~and~~ the side of the trough at somewhat more than ~~to~~ half way down as a fulcrum by which the leverage is exerted on the rack below so as to drive it a head. The head block has at each side ~~and~~ near the lower angle of the lower end thereof, a small, projecting inclined plane rising from said joint towards the opposite angle at the upper & forward end ~~and~~ passing somewhat more than halfway through the side of the trough where a sufficient opening or hollow space is formed to admit of the motion of said plane as it is driven forwards by another similar one advancing from the outside of the trough (where it works upon a pin & joint, upon an upright from the stand below) each being of nearly the same length, so as to pass easily, and the hollow is continued obliquely up, for the purpose of taking out the head block ~~and~~ rubber ~~bar~~ when necessary. Instead of the first plane a small friction roller may be used so as to pass either over or beneath the second plane, on the top of the rubber rack & between the sliding bars is placed a long bar extending from the lower end of the upper rubber to the head block, & has a mortise taken out at the upper end for the purpose of receiving a windlass lever to work upon a pivot there, ~~and~~ the other or lower end of it, is to work between the sliding bars upon a pin or pivot also. The windlass lever is to pass upon a shaft extending across the top of the trough and working in journals and boxes or other fixtures properly adapted thereto, the long arm extending over the lower end of the trough (where the power of whatever kind it is to be driven by will be applied) ~~and~~ the short arm descending by an oblique angle into its position between the sides of the mortise in the bar above described, to which it is united by the pin or pivot. The whole machine may be supported as best adapted either by legs ~~and~~ benches beneath or otherwise. A chain may be substituted for

for the bar just described. *Operation.* The seed being presented at the upper end, & the lever set in motion by bearing down, it raises the last described bar between the sliding bars, and at the same time draws it forward, this of course brings with it the sliding bars & rubber plates by means of the pivot joint connecting them so far as to cause the projecting inclined planes at the sides of the head block to rise over & fall on the other side of those planes from the outside of the friction roller to do the same (now while this is doing the upper rubber plate is consequently raised from the lower one & moved upwards. The long arm in front of the head block drives forward the short one which by its resistance at the fulcrum gives to the short rack beneath it a contrary motion directing the hulls & seeds towards the rubber (and which are admitted in such quantities as may be desired by means of the sliding door, a plate being raised sufficiently for the object. That portion of the unthatched seed which grasps to the lower side of this gate is taken hold of by the teeth of the head block & drawn into the rack, where each stroke of the machine advances it one interval at a time, between the rubber plates. when the backward motion given by raising the lever handle rubs it one way only, & that of course downwards, the bearing to produce which is obtained by the resistance from the fulcrum ends of the sliding bars beneath the friction roller sustained by the seeds & to the fall of the weight of the head block operating on its leverage obtained thereby at the other end. Each fall of the windlass bar raises the upper rubber & each rise thereof causes it to descend by its own weight as its friction roller or inclined plane passes under that of the arm for the outside (now thereby forces the seed downwards between the plates till it comes to the opening at the bottom where it all falls through. The bearing or resistance at the fulcrum may be increased at pleasure by withdrawing the sliding wedge at the top crop bar of the lower gate & facing it downwards during it there will give a harder bite of being the rubber plates nearer together.

What I claim as my invention (and not before known or used)

used in the above described machine is. First, The principle of rubbing out the seed by a repetition of the operation directed always in the same line or by always rubbing one and the same way between two planes. Secondly, The peculiar structure or combination of the several parts viz. The use of the lower gates as constructed. The construction and combination of the rubber frame connecting of the sliding bars & strips composing the rack for the reception of the upper plate also the application of the head block with the friction rollers or inclined planes attached thereto, and that of the inclined planes advancing inwards from the outside. Also the application of the arms from the said head block (or of the rack in front into which they play). Also the sliding door or plate in front of the head block to let in the hulls & seeds, also the lever (windlass) as constructed (and that construction of the trough as described being the provision for receiving the lower rubber plate (or so much of the machinery as is retained above. In testimony) that the above is a full clear and exact description of the construction and operation of my machine as invented or improved by me I have hereunto set my hand this twenty eighth day of August Eighteen hundred and thirty five
